UNITED STATES PATENT OFFICE

FREDERICK WILLIAM SMITH, OF NIAGARA FALLS, ONTARIO, CANADA, ASSIGNOR OF
ONE-HALF TO WILLIAM CHARLES PRETTY, OF NIAGARA FALLS, ONTARIO, CANADA

INDICATOR FOR INTERNAL COMBUSTION ENGINES

Application filed January 6, 1930. Serial No. 418,835.

The invention relates to improvements in indicators for internal combustion engines as described in the present specification and shown in the accompanying drawings which 5 form part of the same.

In setting the valves of an internal combustion engine it is essential that they be properly seated upon the valve facings before adjustment is made. At the moment of 10 firing, the piston of a cylinder is at the top dead centre and as a result it is in an ideal position for the setting of its valves. This position, however, cannot be readily determined, particularly when an engine is of 15 multiple cylinder type such as used for automobiles.

In an application filed by me Serial Number 372,791, dated June 21st, 1929, for "Indicators for internal combustion engines" I dis- 20 closed an indicator for this purpose. The present invention, while employing the same general principle presents certain new and improved features thereover, particularly in 25 the construction and arrangement of the dial which is designed to be more readily removed for substitution of a different dial for chang- 30 ing to a different firing order.

As in the previous application this invention embodies an electro-mechanical arrangement 35 for connection to the ignition circuit in order to signal the firing position of the piston and also to indicate the particular piston of a block brought to top dead centre. Moreover, by turning the crankshaft of the engine 40 the pistons are successively brought to their firing position to enable a mechanic to properly set the valves.

Referring to the drawings; Figure 1 is a 45 side elevation of the invention.

Figure 2 is a face view thereof.

Figure 3 is a sectional view through the casing showing the construction and arrangement of the mechanism.

Figure 4 is a vertical transverse section 50 taken on the line 4-4 of Figure 3, omitting the dial.

Figure 5 is an elevation of the dial.

Figure 6 is an edge view thereof.

Figure 7 is a detail illustrating a pair of 55 terminals for the electric circuit.

Like numerals of reference indicate corresponding parts in each of the figures throughout the drawings.

In the drawings, the reference numeral 10 generally denotes the casing which may be 55 of any suitable shape or design such as that illustrated in order to house the various parts. This casing has a glass front 9 preferably held in a ring 10' threadedly engaged on an annulus 11 so that it may be readily de- 60 tached. The back 12 of the casing is removably secured in place by means of fastening elements 13 engaging lugs 14.

15 is a clamping device for attaching the casing to a part of an internal combustion 65 engine, which clamping device preferably embodies a ball-and-socket joint as at 16 in order that it may swivel.

17 is a slot extending transversely of the top of the casing in close proximity to the 70 glass front 9. Inserted through this slot is a dial 18 consisting of a substantially flat plate having its top edge bent over to form a flange as at 19. Integral with the top edge is a 75 finger grip portion 20 whereby the dial can be readily inserted and removed from the casing. On each side of the casing is a vertical guide as at 21 comprising a flange 22 against which the dial is pressed by a flat spring 23 so as to securely hold it in place 80 and prevent its vibration. Inscribed on the dial is a circular arrangement of numbers designated at A denoting the firing order of a particular engine. It may be desirable to inscribe a firing order on one face and a different firing order on the other face of the dial so that by simply reversing the dial two 85 different orders of firing may be taken care of.

It is suggested that in conjunction with the firing order of an engine the valve clearance may be given for that particular engine such as exemplified at B in order to serve as a ready reference.

In practice it is proposed to have a number of these dials corresponding to particular firing orders of engines. These may be arranged in a set so as to take care of the various firing orders and numbers of cylinders.

ders used on standard internal combustion engines.

24 designates a spindle which is horizontally arranged and disposed concentrically with 5 respect to the circular arrangement of numbers denoting the firing order of an engine on the dial. The frontal end of the spindle projects through a vertical slot 25 in said dial and carries a pointer 26. This pointer operates over the frontal face of the dial in order to coincide with the numerals thereon as it is rotated in a clockwise direction. The spindle is extended through an opening in the back 12 of the casing and has an integral 15 knob 27 by which it may be manually set. The spindle is mounted in a supporting structure 28 which bears an electro-magnet 29. 30 is a terminal of the screw type fitted to the back 12 of the casing and connected to a wire 20 31 leading to the electro-magnet. The other part of the circuit is grounded to the casing. A wire 32 extends from the terminal 30 for connection to the distributor of the engine. 33 is an armature pivoted at 34 to the supporting structure 28 and horizontally arranged so that upon energization of the magnet it will be raised through a small angle of movement. 35 is a ratchet fixedly secured on the spindle 20, which ratchet is engaged by a pawl 36 held by a spring 37. This pawl prevents retrograde movement of the ratchet. 38 is a resilient click fixedly secured to the armature 33 and extended vertically therefrom so 35 as to normally engage the ratchet 35. By this construction, upon energization of the electro-magnet 29 the attraction of the armature 33 imparts a turning movement to the ratchet 35 rotating it a distance of one tooth. 40 Upon deenergization of the magnet the armature drops back by gravitation into its normal position.

39 is a bell fixed to the casing and designed to be struck upon by the striker 40 integral 45 with or secured to the armature 33. 41 is a lamp socket secured to the casing and bearing a bulb 42. One of the terminals of the socket is grounded to the casing while the other is electrically connected to the binding post 43. 50 This binding post is normally connected to the terminal screw 30 by a plate 44 in order that the lamp may be lit coincidentally with the energization of the electro-magnet. This plate is pivoted on the member 30 and has a 55 slot 45 whereby it may be detached from the binding post 43 when it is desired to operate the light by means of an independent circuit. To do this it is merely necessary to slacken the binding post 43 and swing the plate away 60 from it to the position indicated in dot and dash lines, Figure 7: thereupon a separate circuit wire as at 46 is connected to this binding post 43 so as to separately energize the lamp. 65 To employ this invention, the casing is

attached to an engine by means of the clamp 15 and the wire 32 is electrically connected to the distributor. The pointer 26 is so set that upon turning the crankshaft until a piston reaches top dead centre, the energization of the electric magnet 29 will shift the pointer to indicate the particular piston of the block.

Whereas the invention has been shown and described in its application as an indicator 75 for denoting the firing orders of pistons of an internal combustion engine it is also applicable for setting the spark, or what is generally known as "spark timing".

What I claim is:

1. In an indicator, a casing having a slot, a spindle therein, a pointer affixed to said spindle, guides disposed within said casing and led to the slot therein, said guides each including a flange and a flat spring; and a 85 dial inserted in said slot and lodged between the flange and spring of each guide, said dial being slotted to fit over the spindle to the rear of the pointer.

2. In an indicator, a casing having a slot, a spindle therein, a pointer affixed to said spindle, guides disposed within said casing and led to the slot therein, a flat dial inserted in said slot and lodged in said guides, 90 said dial being slotted to fit over the spindle to the rear of the pointer, and an external finger grip integral with said dial.

Signed at Niagara Falls, Ontario, this sixteenth day of December, 1929.

FREDERICK WILLIAM SMITH.
